UNITED STATES PATENT OFFICE.

PHILETUS WARREN GATES, OF CHICAGO, ILLINOIS.

DESIGN FOR A FRAME FOR ROCK AND ORE CRUSHERS.

SPECIFICATION forming part of Design No. 25,426, dated April 21, 1896.

Application filed January 6, 1896. Serial No. 574,556. Term of patent 14 years.

To all whom it may concern:

Be it known that I, PHILETUS WARREN GATES, a citizen of the United States, residing in Chicago, Cook county, Illinois, have 5 invented and produced a new and original Design for Frames for Rock and Ore Crushers, reference being had to the accompanying drawing, forming a part hereof.

In the accompanying drawing the figure is
o a perspective view of my design for a frame
for rock and ore crushers.

The essential feature of my design consists in a casing or frame for rock and ore crushers, comprising a main portion having a central 5 annular flange, an upper portion, and a substantially rectangular lower or base portion.

A A' are the main portion, provided near its central part with a projecting annular portion *a*; B, an upper portion substantially circular in contour; C, a lower projecting portion, and D a rectangular lower base portion, the whole presenting to the eye a harmonious ornate figure, as illustrated in the drawing. 20

I claim—

The design for a frame for rock and ore 25 crushers, herein shown and described.

PHILETUS WARREN GATES.
